FREDERICK APPLEBY BLACK, OF BRIDGEPORT, CONNECTICUT.

INGOT MOLD.

Application filed June 28, 1922. Serial No. 571,444.

To all whom it may concern:

Be it known that I, FREDERICK APPLEBY BLACK, a citizen of the United States of America, residing in Bridgeport, in the county of Fairfield and State of Connecticut, have invented certain new and useful Improvements in Ingot Molds, of which the following is a specification.

My invention relates to ingot molds, and particularly to the configuration of the walls of the mold body, the object of my invention being to so construct the walls of the mold as to progressively and uniformly chill the metal in the mold chamber to the center of the ingot, and thus to avoid segregation, and to prevent the formation of blow holes, gas pockets, etc.

The invention is susceptible of embodiment in molds of various types and shapes, and I have illustrated only certain of the latter in the accompanying drawings, in which—

Fig. 1 is a broken side elevation of an ingot mold, more or less diagrammatically shown, and in which my invention is illustratively embodied;

Fig. 2 is a section on the line 2—2, Fig. 1;

Figs. 3, 4, 5 and 6 are plan views of molds for ingots of different shapes, and in each of which my invention is illustratively embodied.

Various molds have been hitherto employed for the casting of steel ingots with a view to the elimination of gas pockets, blow holes, piping, etc. For the most part the attempts to overcome these difficulties have been in the direction of collapsible molds, special mold caps and bottoms, inclination of the mold walls, etc. So far as I have been able to ascertain, little or no attention has been paid to the relation of the thickness and shape of the mold walls to the size and shape of the mold chamber. The common practice is to make the wall of a mold of uniform thickness at all points around the entire mold at any given cross section, this thickness being apparently chosen with a view to mechanical strength rather than with a view to the chilling effect of the mold wall upon the ingot metal. Thus, molds with walls of 4" thickness are commonly employed for the casting of ingots varying in diameter from 10" to 20". As an incident to this construction, the outer face of the mold wall is substantially parallel to

the inner face thereof. Radiation fins have been sometimes provided on the exterior of the mold; but these fins have been applied in a somewhat hit-or-miss fashion, to add to the radiating capacity of the wall and without any appreciation of the principles upon which my invention is based, nor have such fins accomplished the results which are secured by my invention.

My observations have led me to the conclusion that the relation between the thickness and shape of the mold wall to the size and shape of the mold chamber is of controlling importance if the uniform, progressive freezing of the metal to the center of the ingot is to be obtained. I have found that in ordinary molds now commonly used, the hot metal is progressively chilled inward to an extent corresponding substantially to the thickness of the mold wall, followed by a much slower chilling in the middle of the mold chamber. In other words, a heat interchange occurs between the ingot metal and the mold walls sufficient to freeze the metal inwardly to an extent corresponding to the thickness of the mold walls, but not sufficient to freeze the metal in the central area of the chamber when the thickness of the mold wall is not equal to at least half the diameter of the chamber. Thus, the metal for an ingot of 12" diameter cast in a mold having walls 4" thick is progressively chilled one-third of the way inward from several sides of the mold, while the central area of the ingot chills slowly and remains in objectionably fluid condition with resulting segregation through the absorption of carbon from the solidified outer metal by the still fluid and hot central portion of the charge, and the formation of gas packets, and blow holes. Moreover, even if an 8" ingot were to be cast in a mold with 4" wall, the construction of the latter is still objectionable since at the corner of the mold excess heat exchange takes place, and the chilling of the metal is more rapid at the corners than at the sides, so that the freeze does not progress uniformly in all directions toward the mold center.

The ideal mold, according to my invention, is one in which the size and shape of the mold walls are complementary to the size and shape of the mold chamber, and preferably symmetrical with relation to the center of the latter. In other words, the wall areas

at any given cross section through the mold should be co-extensive with and complementary to a like area of the mold chamber extending to the center of the latter, so that 5 the sum of the cross sectional wall areas should equal the area of the mold chamber in the plane of the section. Exact construction of the mold in accordance with this principle is impracticable by reason of the 10 structural weakness of the mold wall at the joint between adjacent heat absorbing areas thereof; but the configuration of the mold should approach the theoretical as closely as practically possible.

15 The principle may be embodied in molds of any usual shape, and in fact makes possible the casting of ingots in shapes hitherto considered impractical.

The chamber of the mold shown in Figs. 20 1 and 2 is substantially square, with rounded corners. The four walls A, B, C, D of the mold are substantially triangular in cross section, and substantially correspond in area to the complementary triangular 25 areas *a*, *b*, *c*, *d* having their apices in register with the central point X of the mold chamber. The correspondence is not exact by reason of the fact that the corners of the chamber are rounded, and the further fact that the structural strength 30 of the mold necessitates webs E, uniting the bases of the triangular sides. To prevent too rapid heat exchange at the corners of the ingot, and to render the chilling 35 of the ingot as uniform as possible from all exterior points toward the center of the ingot, the sides of the walls A—D are slightly reduced, this reduction being compensated for as closely as possible by the metal 40 in the tie web E. It will be noted, however, that the opposed faces of adjacent areas are so inclined with relation to each other that they intersect substantially at the inner face 45 of the mold wall—and furthermore, that on inward development of the areas into the mold chamber, these faces substantially coincide.

The same idea may be carried out in an 50 oblong mold, as shown in Fig. 3. In this construction the end walls B and D correspond substantially to the similar walls of the square mold in Fig. 2. The walls G and H, however, while having the same lateral 55 inclination of their sides, are truncated to correspond to the truncated areas *g* and *h* of the mold chamber.

When a cylindrical ingot is to be cast, a 60 construction such as indicated in Fig. 4 is employed, in which the wall of the mold presents, in plan, a star shape. The several rays I correspond in area to the complementary inwardly produced areas *i* of the mold chamber, and meet at the center point X of the mold. As in the previous constructions, 65 the heat absorbing wall sections I are neces-

sarily tied together by uniting webs K to give structural strength to the mold.

In Fig. 5 the mold is shaped to produce an octagonal ingot, the several wall sections M corresponding to the complementary 70 areas *m* of the mold chamber. The same idea is carried out in the hexagonal mold shown in Fig. 6, in which the wall sections O correspond to the complementary areas *o* of the mold chamber. In this construction 75 the tie webs P are concave instead of convex, as in Figs. 4 and 5, but serve the same function. It is obvious that the same principle may be applied to molds of other shapes while obtaining the same advantage.

80 It will of course be understood that the mold shown in Fig. 1 is more or less diagrammatic, and that I have not illustrated any particular bottom and top constructions which may be employed to advantage in connection with the present invention to further improve the ingot particularly with respect to piping. These features are not illustrated since the present invention is confined to the body of the mold, which is sufficiently shown 85 to illustrate the principle underlying the present invention.

90 I have found that ingots cast in molds built according to the present principle, progressively chill or freeze the ingot to its center point. While the solidification of the ingot as a whole takes place more rapidly than in molds of the type now commonly employed, the center heat of the ingot prevents the outer shell from solidifying 95 too quickly, and thus avoids surface troubles. I have further found that the slag and gas rise to the top of the ingot, and that the troubles of segregation, blow holes, etc., are minimized, if not completely eliminated, and no decarbonization takes place 100 in the surface, or elsewhere in the ingot. The grain of the latter is very fine and granular, perfectly homogeneous, and without gas pockets and blow holes. If the ingot is not stripped too quickly from the mold, it is practically free from piping, 105 and this can be wholly eliminated by use of appropriate hot tops or sink heads on the mold.

110 The mold structure is rugged and serviceable, and will withstand the hard usage of practical operations without injury. It stands up as well as, if not better than, the average mold, so far as life is concerned.

115 Variations in detail will readily occur to those dealing with the problem, and I do not limit my invention to the precise structure shown.

120 I claim—

1. An ingot mold having walls, the cross sectional area of which corresponds substantially to that of the mold chamber in the plane of the section.
2. An ingot mold having wall areas, the 130

- sides of which converge outwardly, and the cross sectional areas of which are substantially equal to the area of the mold chamber in the plane of section.
5. 3. An ingot mold having wall areas, the sides of which converge outwardly, and the cross sectional areas of which are substantially equal to the area of the mold chamber in the plane of section, and, reproduced 10 inwardly, meet on converging lines in the mid area of the mold chamber.
4. An ingot mold having wall areas, the outline of which in cross section is such that, reproduced inwardly, they define a 15 combined area corresponding substantially to the area of the mold chamber.
5. An ingot mold having wall areas, the outline of which in cross section is such that, reproduced inwardly, they define a combined area corresponding substantially to the area of the mold chamber, the adjacent boundaries of such inwardly produced wall areas being substantially co-incident.
6. An ingot mold having wall areas, the 25 outline of which in cross section is such that, reproduced inwardly, they define a combined area corresponding substantially to the area of the mold chamber, the boundaries of such inwardly produced wall areas being convergent, and adjacent boundaries being substantially coincident.
7. An ingot mold having wall areas, the outline of which in cross section is such that, reproduced inwardly, they define a 30 combined area corresponding substantially to the area of the mold chamber, the boundaries of such inwardly produced wall areas being convergent toward the center of the mold chamber, and adjacent boundaries being substantially coincident.
- 40 8. An ingot mold, the walls of which have relative heat absorbing and radiating capacities predetermined to effect progressive solidification of contained molten metal in areas substantially co-terminous laterally and converging to the mold center.
9. An ingot mold having a wall comprising a series of heat absorbing areas with outwardly converging sides, the outer boundaries of said areas being spaced from the inner face of the mold chamber a distance substantially corresponding to half the least diameter of the mold chamber.
10. An ingot mold having a wall comprising a series of heat absorbing areas with outwardly converging sides, the outer boundaries of said areas being spaced from the inner face of the mold chamber a distance substantially corresponding to half the least diameter of the mold chamber, and said areas having a cross sectional extent which corresponds substantially to the area of the mold chamber.
11. An ingot mold having a plurality of wall areas with outwardly converging sides, the angle between opposed faces of adjacent areas being such that they intersect substantially at the inner face of the mold.
12. An ingot mold having a plurality of wall areas with outwardly converging sides, the angle between opposed faces of adjacent areas being such that they intersect substantially at the inner face of the mold, and the cross sectional configuration of such areas being such that, inwardly reproduced, adjacent boundaries of such areas are substantially coincident, and the combined extent of such areas substantially corresponds to the area of the mold chamber.
13. The method of solidifying ingot metal which comprises freezing the same progressively to the ingot center in areas substantially co-terminous laterally and converging to the mold center.
- In testimony whereof I have signed my name to this specification.

FREDERICK APPLEBY BLACK.
